FRED SMITH, OF STAMFORD, CONNECTICUT.

DECARBONIZING AND PRIMING DEVICE.

1,249,224.

Specification of Letters Patent.

Patented Dec. 4, 1917.

Application filed February 28, 1917. Serial No. 151,515.

To all whom it may concern:

Be it known that I, FRED SMITH, a citizen of the United States, residing at Stamford in the county of Fairfield and State of Connecticut, have invented certain new and useful Improvements in Decarbonizing and Priming Devices, of which the following is a specification.

My invention relates to devices for facilitating the starting of hydrocarbon engines and for decarbonizing the cylinders thereof when necessary or desired. The device is preferably adapted to perform both functions, but may be used for one or the other separately. In any case, it is a simple attachment which is secured to the intake manifold of an engine, the device containing a nozzle, the interior of which is connected to the interior of a cylinder of the engine, so that when air is compressed in the engine cylinder by the cranking of the engine, it will rush through the nozzle. Another passage in the body of the device is connected to the fuel supply of the engine, 25 or when desired, to a vessel containing decarbonizing fluid, and this passage opens into a space surrounding the nozzle. Considering first the priming functions; when the air rushes through the nozzle referred to, it causes the gasoline or other fluid combustible to which the second passage is connected to be sucked up into the space surrounding the nozzle, the latter operating on the injector principle. The gasoline is 30 caught up by the rapid current of air and thoroughly mingled therewith in atomized condition in a suitably formed passage through which the stream of air passes from the nozzle, the combustible spray thus 35 formed passing into the manifold of the engine, from which point it is drawn into a cylinder or cylinders and subsequently compressed and ignited. This is intended as an auxiliary device to be put into operation, 40 when it is desired to prime the engine, by the movement of a valve for opening or closing the gasoline and air supply.

I have also found, as stated, that the described device may, with slight changes, be 45 used for decarbonizing the engine cylinders when desired. That is to say, if the passage in the device which I have described as connected to the gasoline supply of the engine be connected instead to a supply of 50 suitable decarbonizing fluid, such as warm water or alcohol, and the valve opened, after

the engine has been running a sufficient length of time to be thoroughly heated, the water or other decarbonizing fluid will be drawn up by the stream of air or hot gas 60 thoroughly mingled therewith and vaporized. The stream of steam or other vapor thus formed passes into the engine cylinders and efficiently removes the deposit of carbon therefrom. In my preferred device, 65 I combine the priming and decarbonizing functions by providing an additional tube which may be inserted in a glass or vessel containing heated water or alcohol or other decarbonizer, this tube leading into the passage to which the connection from the gasoline supply is connected. In this construction, the tube for drawing up the decarbonizing fluid and the connection extending to 70 the gasoline supply line are both provided 75 with valves, one of which may be closed while the other is open, so that the device will draw up either fuel or decarbonizing fluid in accordance with whether it is desired to prime or decarbonize the engine. 80

Other objects of my invention include details of construction, including a spring-pressed check valve in the passage leading from the mixing chamber of the device into the intake manifold of the engine. I find 85 that a better and stronger stream is projected into the manifold when this valve is used than otherwise.

In order that a clearer understanding of my invention may be had attention is hereby 90 directed to the accompanying drawings forming part of this application and illustrating certain embodiments thereof. In the drawings, Figure 1 represents a partial side elevation of an engine, showing my 95 priming and decarbonizing device mounted upon the manifold thereof and suitably connected, Fig. 2 is a central vertical section taken through the device, Figs. 3 and 4 are cross-sections taken, respectively, on lines 100 3—3 and 4—4 of Fig. 2, and Fig. 5 is a plan view of the device shown partly in section.

Referring to the drawings, the priming and decarbonizing device is represented at 1 mounted upon the manifold 2 of an engine, 105 the cylinder or cylinders of which are contained within the casing 3, is being understood that my invention is applicable to engines having any number of cylinders or a single cylinder. The device is secured to 110 the manifold 2 by screwing the cylindrical portion 4 of the device into a suitably

threaded opening in the manifold, a lock nut 5 preferably being additionally used.

The casting 1 has passages 6 and 7 extending into the same from one surface thereof, these passages being connected respectively to the interior of a cylinder and to the gasoline supply (or decarbonizing fluid supply, or both, as stated). To this end, passages 6 and 7 have connections 8 and 9 screwed into their outer ends to which are secured tubes 10 and 11. Tube 10 is connected to the interior of any cylinder by any convenient opening therein, as stated, such, for example, as the spark plug 12. Tube 11 may be connected to the line of gasoline supply, preferably by connecting it by means of a T 13 in the pipe 14 extending from the gasoline supply tank (not shown) to the carburetor 15.

Passages 6 and 7 are opened or closed by means of a rotary tapered valve 15^x, which extends across the passages and is held in position by a spiral spring 16. A handle 17 is secured to the valve and may be oscillated between stop pins 18 to open or close the valve. The handle may extend to any point convenient for the operator and serves to open both passages 6 and 7 simultaneously, as shown in Figs. 3 and 4, when it is swung away from its normally closed position.

The nozzle of the injector type is shown at 19 and may be provided with screw-threads and screwed into position in a recess appropriately threaded to receive the same. The outer end of member 19 is solid and adapted to fill the opening. The inner end of member 19 is provided with a tapered delivery portion 20, which is located in a converging passageway 21 extending through the cylindrical portion 4 of the device toward the interior of the manifold.

The passageway 6 for the compressed air leads through a peripheral groove 22, formed about member 19, to an opening 23 extending into the interior thereof, which opening connects with the axial bore 24, which extends from that point through the nozzle 20. The passage 7 for the liquid fuel opens into the space surrounding nozzle 20.

A check valve should preferably be interposed in the path of the liquid fuel drawn up through passage 7. My preferred construction for this purpose is shown in the drawings and comprises a ball valve 25 pressed against a seat by a spring, the opposite end of which rests against a screw plug 28, which may be used to close the recess in which the ball and spring are located. A recess 29 is formed in horizontal alignment with ball 25, this recess constituting part of the passage 6 for the compressed air. A piston 30 is slidably mounted in recess 29 and has a stem 31, the opposite end of which is adapted to press against ball 25, stem 31 being slidably mounted in a hori-

zontal cylindrical passage extending between recess 29 and the recess in which ball 25 is mounted. The outer end of recess 29 may be closed by a screw plug 32. The passage 7 proper terminates at the recess in 70 which ball 25 is seated, but a continuation of the same 7' extends from the rear surface of seat 26 to the annular space surrounding nozzle 20.

When valve 15^x is open and the shaft of 75 the engine is rotated as by cranking the same, compressed air will flow through passage 6 as soon as compression takes place in the cylinder to which spark plug 12 is attached. As this air passes through recess 80 29 it presses plunger 30 to the left, referring to Fig. 2, so that ball 25 is moved away from its seat, opening a passageway between passages 7 and 7'. The air rushing through the bore 24 of the injector nozzle causes a 85 powerful suction in the space surrounding the nozzle, drawing up gasoline through passages 7, 7', the mingled spray of air and gasoline being thrown into the manifold with considerable force. Preferably the 90 atomized stream is not injected axially of passage 21 into the manifold, as it would thereby be directed against the rear wall of the manifold. I prefer to close the end of passage 21 with a screw plug 33 and cause 95 the spray to be directed in opposite directions through passages 34, 34, which cross passage 21 at a right angle, as shown in Fig. 5. The spray will thereby be directed in opposite directions lengthwise of the two 100 branches 2^a and 2^b of the manifold 2, so that the same will be drawn into any cylinder in which suction is taking place.

In my preferred construction, as stated, I provide a spring-pressed check valve in 105 the delivery opening of the device. This preferably takes the form of a ball valve 35 which is pressed by a spring 36 into contact with a seat 37, the spring being coiled about a stem secured to the plug 33 110 and adapted to form a stop for ball 35. Ball 35 when resting against its seat is a short distance in advance of the delivery end of nozzle 19, the space 38 between the ball and the end of the nozzle constituting 115 a mixing chamber in which the air passing through the nozzle and the fluid drawn up into space 21 surrounding the same are mingled. I have found that when the spring-pressed valve 35 is used, a stream or jet of greater force is thrown into the manifold than when no such check valve is used.

The device has been so far described in detail as adapted for priming the engine. As stated, it may be used for decarbonizing the engine cylinders, when desired, by simply connecting the passage 7 with a supply of decarbonizing fluid instead of the fuel supply as shown. I prefer, however, to combine the two functions 120 125 130

in one apparatus and accordingly have illustrated a screw-threaded opening 39 extending through a boss 40 in the side of the device, opening 39 being connected by a passage 41 with the passage-way 7. A short curved pipe 42 is connected with a screw-threaded plug adapted to screw into opening 39, the plug being provided with an integral nut 42 and a valve 43 being provided in an enlargement of the pipe 44.

Also, the pipe connection 11 extending to the fuel supply line 14 is provided with a valve 45. When the device is to be used for priming, valve 43 is closed and valve 45 is opened. When, however, it is desired to use the device for decarbonizing the cylinders, valve 45 is closed, valve 43 is open and the lower end of pipe 42 is inserted in a vessel such as the can 46 containing water, alcohol, or other desired decarbonizing fluid. If water is used, it is preferable that the same should be hot, in which case it is immediately turned to steam by the hot air rushing from the engine cylinder through nozzle 19, assuming that the engine is well heated when the device is used for decarbonizing. A short application of the device for this purpose is sufficient to thoroughly cleanse the interiors of the cylinders.

Whether the ball valve 25 is used or not, a check valve should be employed in passage 7, to positively prevent the possibility of air from the nozzle pressing down into the fuel supply. This is shown as a simple ball 47 resting on a seat 48 in connection 9. Any downward pressure in passages 7, 7' forces this ball against its seat, whereas it is lifted to permit the upward flow of fuel when suction is created in passages 7, 7', by the rush of air from the nozzle past ball 35 into the manifold.

The use of the injector principle as described renders the device efficient, as stated, both for facilitating the starting of an engine when cold and for decarbonizing the same when hot. The body portion 19 of the injector nozzle is screwed into place to fit snugly against a shoulder formed in the casting, as shown, to prevent leakage of air past the same and the check valve in passage 7, of which the form described is preferred, serves to prevent passage of gasoline past the same at all times except when compressed air is rapidly passing through the injector nozzle, since the ball 25 is firmly seated against its seat except at such times as the pressure in recess 29 overbalances spring 27.

What I claim is:—

1. In an attachment for hydrocarbon engines, a body having a cylindrical offset portion adapted to be inserted in an opening in an intake manifold, and having a converging chamber extending through said offset portion, a nozzle mounted in said

body having a tapered delivery end extending into said chamber, said nozzle having an axial bore extending from said end to a point to the rear thereof, and there communicating with a peripheral groove with in the body, said body having passages extending from a surface thereof to said groove and to the space surrounding the delivery end of the nozzle respectively, and a valve mounted in said body to simultaneously close and open said passages, substantially as set forth.

2. In an attachment for hydrocarbon engines, a body adapted to be attached to an intake manifold, and having a delivery passage therein adapted to deliver into the manifold, a nozzle mounted in said body with its delivery end in said passage, with a space constituting part of said delivery passage surrounding said end, said body having passageways extending from a surface thereof into the interior of said nozzle and into said space respectively, with an enlarged space forming part of said first passageway, means for closing and opening said passageways, a check valve additionally controlling said second passageway, a spring normally holding said check valve in closed position, and a piston in said enlarged space, connected to said check valve, and adapted to move said valve to open said second passageway when sufficient pressure exists in said first passageway to overcome said spring, substantially as set forth.

3. In an attachment for hydrocarbon engines, a body adapted to be attached to an intake manifold and having a delivery nozzle adapted to deliver into the manifold with a vacuum chamber surrounding the nozzle and a mixing space between the delivery end of the nozzle and the manifold, passages adapted to lead compressed air into the nozzle and liquid fuel or other liquid into the vacuum chamber, a valve for closing said second passage, means controlled by passage 110 of compressed air through said first passage for opening said valve, and manual means for opening and closing said first passage, substantially as set forth.

4. In an attachment for priming hydrocarbon engines, the combination of a body adapted to be secured to an intake manifold, said body having a delivery portion adapted to be inserted in an opening in said manifold, a tube extending from said body to a connection with the liquid fuel supply pipe leading to the carburetor, a second tube connecting said body through an opening in any cylinder of the engine with the interior thereof, an injector nozzle mounted within said body, and having a bore connected with said second tube, by a passage through said body, said body also having a passage connecting said first tube with a space surrounding the nozzle, and a mixing delivery

space between the nozzle and manifold, in the delivery portion of said body, and manual valve means for controlling the flow of compressed air and fuel into said body, substantially as set forth.

5. In an attachment for hydrocarbon engines, the combination of a body adapted to be secured to an intake manifold, with a delivery portion adapted to be fitted into an 10 opening in the manifold, a converging chamber extending through said portion, an injector nozzle mounted within the body, having a tapered delivery end extending into said chamber, said body having passages extending 15 from a surface thereof to the interior of said nozzle and to the space surrounding the delivery end of the nozzle respectively, connections for leading air from a cylinder of the engine, when compressed, 20 into the passage leading into the nozzle, and liquid into the passage leading to said space by suction, and valve means for controlling the flow of air and liquid, substantially as set forth.
- 25 6. In an attachment for hydrocarbon engines, the combination of a body adapted to be secured to an intake manifold having a nozzle therein adapted to deliver into the manifold with a chamber surrounding the 30 nozzle and a mixing space between the delivery end of the nozzle and the manifold, a

passage adapted to lead compressed air into the nozzle, and a passage adapted to lead fluid into the chamber surrounding the nozzle; a pipe adapted to connect said second 35 passage with a fuel supply, and a pipe adapted to connect said second passage with a supply of decarbonizing fluid, said pipes being provided with valves, substantially as set forth.

- 40 7. In an attachment for hydrocarbon engines, the combination of a body adapted to be secured to an intake manifold, said body having a delivery passage therein positioned to deliver into an opening in the manifold, a 45 nozzle having a delivery end extending into said passage, a spring-pressed check valve in said passage, adapted to be opened by pressure of fluid issuing from said nozzle, said body having passages extending into 50 the interior of said nozzle and into the space surrounding the delivery end of said nozzle respectively, and means for closing and opening said passages, substantially as set forth.

This specification signed and witnessed this 26th day of February, 1917.

FRED SMITH.
